FOREIGN PATENT DOCUMENTS

WO 98/51590 11/1998

Primary Examiner — Thomas Johannes

(74) Attorney, Agent, or Firm — Hoffmann & Baron, LLP

CLAIM

The ornamental design for a closable product package, as shown and described.

DESCRIPTION

FIG. 1 is a front perspective view of a closable product package showing our new design;

FIG. 2 is a front elevational view thereof;

FIG. 3 is an end elevational view thereof;

FIG. 4 is a rear elevational view thereof;

FIG. 5 is a side end elevational view thereof;

FIG. 6 is an opposite side end elevational view thereof; and,

FIG. 7 is a perspective view thereof in an opened usage condition.

The broken line portion of FIG. 7 is included to show unclaimed subject matter and forms no part of the claimed design.
